UNITED STATES PATENT OFFICE.

SIMON MORRISON, OF BROOKLYN, NEW YORK.

VANITY CASE.

Application filed March 8, 1924. Serial No. 697,840.

To all whom it may concern:

Be it known that I, SIMON MORRISON, a citizen of the United States, residing at Brooklyn, in the county of Kings and State 5 of New York, have invented certain new and useful Improvements in Vanity Cases, of which the following is a specification.

My said invention relates to vanity cases and it is an object of the same to provide an 10 improved and simplified construction thereof.

Another object of the invention is to provide a convenient device in connection with a vanity case for making brief memoranda 15 as for shopping purposes.

Referring to the accompanying drawings which are made a part hereof and on which similar reference characters indicate similar parts,

20 Figure 1 is a perspective of my device in open position, and

Figure 2, a similar perspective with the parts in another position.

In the drawings reference character 10 indicates the box or container which forms the 25 lower member of the vanity case and which is adapted to have a compact located on the bottom thereof in ordinary manner or which may be used as a container for other things 30 if preferred. A bead is provided at 11 a little below the upper rim of the box, this bead serving to limit the downward movement of the cover member 12 hinged at 13 to the box. Within the box and preferably 35 below the bead 11 a support 14 is provided which preferably bears against the bottom of the box at one edge and is secured to the wall of the box by a rivet 15. The support at its upper edge carries certain lugs 40 of a hinge 16 whereby an annulus 17 is pivotally connected to the box, the closure carrying lugs coacting with those first referred to for supporting the pintle of the hinge. A coil spring 18 may be provided in connection 45 with the hinge for moving the closure toward open position in which case the flange 19 of the annulus by means of which a mirror 20 is held in place may be so formed as to fit closely within the upper 50 margin of the box to hold the member 17 normally in closed position.

At the front side of the box farthest from the hinge 13 a detent 21 is provided, said 55 detent being preferably formed in one piece or being secured to the free end of the member 14 which is made of resilient material

so that the lip 22 of the lid can snap over and be held by the detent. A finger piece 23 is also formed integral with or secured to the forward end of member 14 and it will 60 be obvious that by pressing on the finger piece the detent 21 is forced back to release the cover.

At the top or back of the closure consisting of the annulus 17 and the mirror 20 an 65 open space is left at the rear of the mirror and in this I locate a sheet 24 of celluloid or other convenient material at the back of the mirror so as to be exposed by said opening whereby the memoranda can be made 70 with a pencil or the like on the exposed side of the celluloid. It will be understood that paper or slate or any other material on which marks can readily be made and erased can be substituted for celluloid. The opening is circular but a widened part 25 is preferably formed adjacent the hinge to strengthen the frame at this point and also to afford space for a legend such as "Notes" 75 or the like.

It will be understood that a rouge compact or other toilet device may be supported in the cover 12 and that other toilet requisites may be substituted for the compact in container 10. Many other additions and 80 changes in my device will be obvious to those skilled in the art and therefore I do not limit myself to what is shown in the drawings and described in the specification, but only as indicated in the appended 85 claims.

Having thus fully described my said invention, what I claim as new and desire to secure by Letters Patent, is:

1. In a vanity case, a box having a cylindrical wall, a cover hinged to one side of the box, an arcuate support lying against a part of said wall, an annulus hinged to the support approximately 90° from said cover, and a mirror on said annulus, substantially 90 as set forth.

2. In a vanity case, a cylindrical box, a cover for said box and an arcuate support secured internally of said box and having a mirror carried by said support said support 105 having integral lugs at the upper edge of the support near one end thereof to receive a pintle carried by said mirror and a lug at said edge near the other end to hold the cover of the box closed, substantially as set 110 forth.

3. A vanity case comprising a box, a cover

for said box, a support conforming throughout its length to the inner side wall of the box secured thereto, a mirror carried thereby, said support having one end forming an element of a hinge and having its other end forming a catch for the cover of the box, substantially as set forth.

4. A vanity case comprising a box, a cover hinged thereto, a support extending along the side wall of the box and secured thereto, one end of said support forming an element of a hinge for a mirror and the other end of said support having a resilient extension forming a detent for holding the cover of the box closed, substantially as set forth.

5. A vanity case comprising a box, a cover hinged thereto, a support secured within the box to the side wall thereof, one end of said support forming a pivoted support for a mirror and the other end of said support having a resilient extension forming a de-

tent for holding the cover of the box closed and a finger piece on said extension for releasing said detent, substantially as set forth.

6. A vanity case comprising a box, a cover for said box, a supporting element secured within one side of said box, said supporting element conforming to the shape of the side of the box to which it is attached and having one side constituting an element of a hinge for a mirror one end of said supporting element forming a catch for the cover of the box, substantially as set forth.

In witness whereof, I have hereunto set my hand at Providence, R. I. this 5th day of March, A. D. nineteen hundred and twenty-four.

SIMON MORRISON
